TRAINING MECHANISM FOR ORDNANCE.

No. 408,882.

Patented Aug. 13, 1889.

UNITED STATES PATENT OFFICE.

ALFRED C. KOERNER, OF PARIS, FRANCE, ASSIGNOR TO THE HOTCHKISS
ORDNANCE COMPANY, (LIMITED,) OF LONDON, ENGLAND.

TRAINING MECHANISM FOR ORDNANCE.

SPECIFICATION forming part of Letters Patent No. 468,882, dated August 13, 1889.

Application filed April 9, 1889. Serial No. 306,520. (No model.) Patented in France January 16, 1889, No. 182,331.

To all whom it may concern:

Be it known that I, ALFRED C. KOERNER, a subject of the Queen of England, residing in Paris, France, have invented certain new and useful Improvements in Training Mechanism for Ordnance, fully described and represented in the following specification and the accompanying drawings, forming a part of the same, the said improvements being embodied in French Letters Patent, No. 182,331, dated January 16, 1889.

This invention relates to improvements in training or pointing apparatus for rapid-firing or other guns.

It is the object of the present invention to provide mechanism for this purpose by which the operations of pointing both horizontally and vertically will be rendered easier and can be accomplished with greater facility and rapidity than in mechanisms heretofore commonly used for this purpose.

It is also the object of the present invention to so construct and arrange the mechanism for rough pointing horizontally that when it is desired to move the gun to any great extent horizontally in rough pointing this mechanism may be thrown out of operative connection with the gun-carriage, so as not to interfere with the horizontal movement of the gun.

The mechanism for fine pointing horizontally consists, briefly, of a worm-wheel upon the lower part of the gun-carriage, with which engages a worm mounted on a shaft journaled in a frame pivoted to the upper part of said carriage, said shaft and worm being operated through suitable connections by means of a shaft and hand-wheel extending to the rear of the gun to cause the upper part of the carriage, and with it the gun, to revolve in a horizontal path upon the lower part of the carriage. The frame in which the worm-carrying shaft is mounted is connected to a directing-lever, so that when the latter is raised the worm will be thrown out of engagement with the worm-wheel upon the lower part of the gun-carriage, and thus permit the movement of the gun horizontally to be accomplished quickly and easily in rough pointing.

The mechanism for pointing vertically consists of an elevating-screw connected to the

under side of the gun and working in a nut pivoted in arms upon the upper part of the gun-carriage, said screw being raised and lowered to correspondingly move the gun through suitable connections by means of a hand-wheel located at the rear of the gun.

In the accompanying drawings, Figure 1 is a perspective view of a gun and its carriage equipped with my improvements. Fig. 2 is a side elevation, partly in section, of the same. Fig. 3 is a plan view of the same. Fig. 4 is a vertical section on the line 4 of Fig. 3, the gun being removed; and Fig. 5 is a section taken on the line 5 of Fig. 2.

The gun A illustrated in said drawings is of the ordinary Hotchkiss rapid-firing type. It is to be understood, however, that the improvements constituting the present invention are equally applicable to guns of other types. The gun A is mounted in the usual manner upon its carriage, which is made in two parts—viz., a base a and an upper part b. The gun is trunnioned upon the upper part b of the carriage. The upper part b of the carriage is mounted upon the base a, so as to be free to be revolved thereon. The base a of the carriage is circular in form at its upper edge, and is provided with a worm-wheel c, with which normally engages a worm d. The worm d is carried by a shaft e, journaled in bearings formed upon the lower end of a U-shaped frame f, suspended pivotally from the upper part b of the carriage by means of pivots h entering bearings i, provided in the upper ends of the frame upon opposite sides of the gun A. The shaft e has secured to it at one end a bevel gear-wheel l, with which engages a second gear-wheel l', carried by a shaft k, extending toward the rear of the gun and provided at its end with a hand-wheel j, located in convenient position to be grasped by the gunner. The shaft k is journaled in a downward extension y of the shoulder-piece v, forming one with the directing-lever g, which in turn is made integral with or connected to the frame f.

With the mechanism thus constructed and arranged the operations of rough pointing and fine pointing horizontally are accomplished in the following manner: To move the

gun A horizontally to any great extent to approximately the direction in which it is desired to fire, the gunner will raise the directing-lever *g* to the position shown by dotted lines in Fig. 2. The raising of the directing-lever to this position will swing the frame *f* backward, and thus take the worm *d* out of engagement with the worm-wheel *c*. With the worm *d* in this position the gunner by means of the lever *g* will revolve the gun and the upper part *b* of the carriage upon the base *a* into the desired position horizontally. By then lowering the lever *g* the worm *d* and worm-wheel *c* will be again brought into engagement. To adjust the gun accurately horizontally to bring it in line with the object at which it is desired to fire, the gunner will, by turning the hand-wheel *J* and shaft *k*, operate the bevel gear-wheels *l* and through them cause the revolution of the shaft *e* and its worm *d*. As the worm *d* is thus revolved, it will travel around the worm-wheel *c* upon the base *a* of the carriage, and being connected to the upper part of said carriage will cause it, and with it the gun, to revolve upon the base *a*. This movement will be continued until the gun is properly pointed horizontally. The gun will then be adjusted vertically to proper position for firing by means of the mechanism which will now be described. This mechanism consists of an elevating screw *m*, pivoted to the under side of the gun A, near its rear end, by means of a pivot *n*, its lower end working in a screw-threaded nut *o*, mounted and turning in a collar *o'* pivoted between arms *p*, projecting rearwardly from the upper part *b* of the carriage. The nut *o* is provided at its lower end with a worm-wheel *t*, with which engages a worm *t'*, carried by a short shaft *s*, connected to a rod *r*, which in turn is connected to a shaft *z*, mounted in an extension of the directing-lever *g* and provided with a hand-wheel *q*. The shaft *z* and the shaft *s* are connected to the rod *r* by universal joints *u u'*, respectively, by means of which connection they are adapted to angular motion caused by the elevation and lowering of the gun from its horizontal position and by the raising and lowering of the directing-lever *g*. To elevate or depress after the gun has been properly adjusted horizontally, the gunner, by turning the hand-wheel *q* and shaft *z*, will, through the rod *r*, shaft *s*, worm *t'*, and worm-wheel *t*, turn the nut *o* about the elevating-screw *m* and cause said screw to move upward in said nut, thus depressing the gun for firing. To elevate, the gunner will turn the hand-wheel in the opposite direction. When the gun has been pointed as described, the gunner, by drawing upon the lanyard *w*, will cause its discharge. The lan-

yard *w* will preferably be located, as shown in the drawings, with its end connected to a handle *x*, mounted in the extension *y* of the shoulder-piece *v*, beneath the hand-wheel *j*, 65 in substantially the manner shown in my Letters Patent No. 394,190, thus bringing the firing mechanism into convenient position to be operated by the gunner without changing his position after the operations of aiming. 70 By thus constructing and locating the mechanisms for rough pointing and fine pointing horizontally, pointing vertically, and for firing, the several mechanisms are within easy reach of the gunner without changing his 75 position at the rear of the gun, thus insuring facility and rapidity in the various movements and the firing of the gun.

It will be obvious that the connections for operating the mechanisms for fine pointing 80 horizontally and vertically may be somewhat modified without departing from the spirit of my invention.

What I claim is—

1. In a rapid-firing or other gun, the combination, with its carriage in two parts *a b*, of the worm-wheel *c* upon the lower part *a* of said carriage, the worm *d*, engaging therewith and secured to a shaft *e*, mounted in a frame suspended pivotally from the upper 90 part *b* of said carriage, the hand-wheel *j*, shaft *k*, and connections for rotating said shaft *e*, substantially as described. 85

2. In a rapid-firing or other gun, the combination, with its carriage in two parts *a b*, 95 of the worm-wheel *c* upon the lower part *a* of said carriage, the worm *d*, engaging therewith and secured to a shaft *e*, mounted in a frame *f*, suspended pivotally from the upper part of said carriage, bevel gear-wheels for 100 rotating said shaft, the hand-wheel *j*, and shaft *k*, for operating said gear-wheels, and the directing-lever *g*, connected to the frame *f* to swing the same, substantially as described. 105

3. In a rapid-firing or other gun, the combination of the elevating-screw *m*, pivoted to the gun and working in a nut *o*, suspended from the gun-carriage, the worm-wheel *t* upon said nut, the worm *t'*, engaging therewith, the 110 shafts *s* and *z*, connected to the rod *r* and carrying the worm and hand-wheel, respectively, and the hand-wheel *q*, for operating said shafts and rod, substantially as described. 115

In testimony whereof I have hereunto set my hand in the presence of two subscribing witnesses.

ALFRED C. KOERNER.
